UNITED STATES PATENT OFFICE.

GEORGE W. TRIBBEY, OF MARSHFIELD, OREGON.

DEVICE FOR PROTECTING RECEPTACLES AGAINST FREEZING.

1,226,030.

Specification of Letters Patent.

Patented May 15, 1917.

Application filed July 31, 1916. Serial No. 112,389.

To all whom it may concern:

Be it known that I, GEORGE W. TRIBBEY, a citizen of the United States, residing at Marshfield, in the county of Coos and State 5 of Oregon, have invented or discovered certain new and useful Improvements in Devices for Protecting Receptacles Against Freezing, of which the following is a specification.

- 10 It is well known that, with water cooled internal combustion engines, and particularly those used for automobiles, there is a liability of considerable damage being caused if the water in the cooling system is 15 allowed to freeze. This is also true in other cases as in water tanks or the like. The present invention relates to a device or arrangement which is intended to protect such engines or receptacles against freezing.
- 20 The objects of the present invention are to provide a simple and efficient device for protecting receptacles from being injured by the freezing of any liquid therein; to provide a safety device for use in connection 25 with vessels containing liquids, which will break and permit the discharge of the liquid under freezing conditions; and in general to provide such a protecting device as will be more fully described hereinafter.
- 30 In the accompanying drawings illustrating this invention:

Figure 1 is a side view of a preferred form of my improved protecting device;

Fig. 2 is a horizontal sectional view taken 35 on the line 2—2 of Fig. 1; and,

Fig. 3 is a vertical sectional view showing a modified form of construction.

As shown in these drawings 4 represents 40 a receptacle which may indicate the water jacket, or any other portion of the water cooling system of an internal combustion engine, or any vessel which it is desired to protect against freezing. In order to protect such vessel or receptacle, I provide a safety 45 device which is intended to be affected by the low temperature so as to permit the escape of the liquid in the receptacle before it freezes. In the arrangement shown in Figs. 1 and 2, I provide two elbows 5 and 6 which 50 are tapped into the bottom or lowermost part of the receptacle 4. A tube 7 of glass or other suitable frangible material is inserted between the opposed open ends of the elbows or connections 5 and 6 so that the 55 liquid or water in the receptacle 4 will fill such tube. This tube is preferably made

with two constricted portions 8, 8 with an enlarged portion 9 between them. When the water reaches a freezing temperature, the portion which is in the glass tube, being 60 most exposed, will freeze first, and the small amount of water between the constricted portions 8, 8, which will be most readily frozen, will cause the tube to be broken at this point and ordinarily would allow the 65 escape of water through the broken ends of the tube. However, in order to more positively insure the free escape of the water, I prefer to insert a spring 10 between an abutment 11 in the elbow 5 and a ring or washer 70 12 at the end of the tube 7. A packing ring 13 is inserted between the washer 12 and the end of the tube in order to make a tight closure. A similar packing ring 14 is inserted between the opposite end of the tube and 75 a shoulder or abutment 15 in the elbow 6. When the tube 7 is broken, the spring 10, which is under compression, will force the broken end of the tube out of the elbow 5 and will leave a free passageway for the escape 80 of the water so that the water will not be apt to freeze at the discharge opening.

By means of this device it will be readily seen that, when the liquid or water reaches a freezing temperature, the safety tube will 85 be broken and will permit the escape of the water from the engine or other receptacle and will prevent the engine from being broken or injured by the freezing water.

In the modified form of construction 90 shown in Fig. 3, a threaded plug 16 is inserted in the lower part of the receptacle 17. A tube 18, which is preferably of tapered or conical form and closed at its outer end, is provided with an outwardly projecting 95 flange 19 which engages with the outer end of the plug 16, a washer 20 being inserted to insure a tight closure. A flanged collar or union 22 is used for connecting the tube 18 with the plug or connection 16. The operation of this form of the device is substantially the same as that above described. The tube 18, being relatively small, will freeze first and as soon as it is broken, will permit the escape of water from the receptacle 17. The protective device or tube may be located in such position that it might be accidentally broken so that when necessary I provide a shield or guard therefor. The guard 23 as shown in Fig. 3 is made of 110 any suitable material such as perforated metal or woven wire, and is held in position

by being clamped between the union 22 and the shoulder on the plug 16. When the device is used in connection with an automobile engine, this guard may also serve to somewhat protect the tube 18 from the cold when the car is in motion, so that it will not be inadvertently frozen when there is no likelihood of the water freezing in the engine or radiator.

10 It will be noted that this device can be easily applied to engines or other receptacles and a supply of the breakable members may be kept on hand so that when the temperature goes below the freezing point the 15 only part which will be injured is the glass tube which may be replaced at a small cost and thereby save the possibility of a serious and expensive injury. It will also be noted that various forms of tubes or frangible 20 members may be used in accordance with this invention, and such tubes may be arranged or connected in various ways without departing from the scope of this invention, and therefore I do not wish to limit myself 25 to the particular connection shown except as specified in the following claims in which I claim as my invention—

1. The combination with a receptacle, of a glass member having a connection between the same and the vessel, and adapted to be broken by the freezing of water therein, and a spring associated with said glass member and adapted to eject the broken portion of the member out of the connection, in order to make a free passageway for the water.

2. The combination with a receptacle for water, of a frangible member, a connection between the frangible member and the lower

portion of the receptacle, a spring associated with said frangible member and adapted to force the broken portion thereof from the connection when the member is broken, and a perforated guard around said frangible member, for protecting the same and also for holding the broken portions thereof in case the member is broken.

3. In a device of the character set forth, the combination of a vessel, a glass tube, connections between the tube and the vessel to permit the water in the vessel to enter the tube, and a spring associated with said tube, the arrangement being such that the tube will be broken by the freezing of the water therein before the water in the vessel is frozen, and when broken will permit the escape of water from the vessel, said spring serving to eject a portion of the broken tube to make a free passageway for the water.

4. The combination with a receptacle, of a glass tube having a reduced portion therein, connections from the end of the tube to the vessel, and a spring arranged between one end of the tube and its connection so that the spring will force the end of the tube out of the connection when the tube is broken.

5. In a protective device of the character set forth, the combination with a vessel or receptacle, of a pair of connections, a glass tube having constricted portions forming a restricted area therebetween, and having its ends fitting in said connections, and a compression spring arranged between one of said ends and its connection and adapted to eject said end when the tube is broken.

GEORGE W. TRIBBEY.
